UNITED STATES PATENT OFFICE.

JOHN W. GORRELL, OF CONNELSVILLE, MISSOURI.

LUGGAGE CARRIER.

Application filed March 8, 1922. Serial No. 542,188.

To all whom it may concern:

Be it known that I, JOHN W. GORRELL, a citizen of the United States of America, and resident of Connelsville, in the county of 5 Adair and State of Missouri, have invented certain new and useful Improvements in Luggage Carriers, of which the following is a specification.

This invention relates to luggage carriers 10 for automobiles, and particularly to a detachable luggage carrier adapted to be associated with the running or foot board of an automobile.

An object of this invention is to provide 15 a luggage carrier of the character indicated that can be made relatively wide, as compared with the width of the running board, in order that the capacity of the carrier will be increased, as compared with the capacity 20 of carriers now in common use; and the said invention further contemplates the provision of novel means whereby the carrier can be readily applied to or removed from the running board of an automobile, and the 25 invention has further reference to novel means whereby the carrier is anchored at the outer edge of the running board in such a manner as to obviate accidental dislodgment or displacement of the running board, while 30 at the same time affording means for its detachment without manipulation of fastenings such as bolts, nuts or the like.

It is a further object of this invention 35 to produce a luggage carrier, the contents of which augments the efficiency of its means of anchorage to the running board, due to the weight of the said contents.

With the foregoing and other objects in view, the invention consists in the details 40 of construction, and in the arrangement and combination of parts to be hereinafter more fully set forth and claimed.

In describing the invention in detail, reference will be had to the accompanying 45 drawings forming part of this application wherein like characters denote corresponding parts in the several views, and in which—

Figure 1 illustrates a perspective view of 50 a running board showing a device embodying the invention applied thereto;

Figure 2 illustrates a sectional view of the running board showing the luggage carrier in end elevation; and

Figure 3 illustrates a sectional view on 55 the line 3—3 of Figure 1.

In carrying the invention into practice, I prefer to construct it of metal rods of relatively small gage, but the length of the carrier and its width must be taken into consideration in the selection of material of 60 proper size and strength.

In the present embodiment of the invention, the carrier is illustrated as comprising an outer frame-like structure consisting of 65 a horizontally disposed top rail 5 and a parallel bottom rail 6 that may be joined together by vertical or otherwise related ends 7 and 8. The end 7 of the frame, in this embodiment of the invention, is provided with an integral arm 9 which extends inwardly over the running board 10 and it is anchored in place by reason of the fact that the end of the arm extends through an eye bolt 11 which may be used as one of the 70 fender fastenings by which a fender is connected to the running board, as is a common construction in automobiles. Of course any equivalent device may be employed as an anchorage for the inner end of the arm 75 which is shown as having its end 12 bent in order that a pull on the arm longitudinally, will cause the binding of the end of the arm and the anchorage that will prevent the dislodgment of the arm from the 80 anchorage. Another arm 13 extends from the frame and it is of the same construction as the arm 9 and is applied to an anchor 14, similar to the anchor 11. An intermediate horizontal frame member 15 extends 85 parallel with the upper and lower sections 5 and 6 of the frame, and the said member 15 may have its ends anchored to the ends 90 of the frame in any appropriate way.

Between the ends of the frame there is a 100 post or brace 16 that is preferably anchored to the members 5, 6 and 15 of the frame, and this post, in the present embodiment of the invention, has an extension 17 which projects inwardly and terminates in an upward 105 extension 18 adapted to lie against the under surface of the running board when the parts are in assembled positions, as shown in Fig. 3.

The frame is made of resilient material 110 in order that it may be sprung sufficiently to permit the insertion of the extension 17 under the running board, and hence when

the guard is to be removed, it will be necessary to spring or distort the frame by pressing it inwardly at the top to cause the extensions to pass the edge of the running board when the guard is lifted.

As a means for preventing the dislodgment of packages or the like from the ends of the carrier, end guard 19 and 20 are provided and they preferably extend from the 10 upper portion of the frame at the end and are joined to or formed continuous with a horizontal member or rod 21 which lies on the extension 17, and in the interests of the 15 rigidity of construction, may be secured to it in appropriate way, as by welding or the like.

It will, of course, be understood that it is immaterial in the production of a luggage carrier embodying the invention, in what 20 manner the elements or rods of which the carrier is formed are connected together at their intersections, since one skilled in the art will understand that they may be riveted or otherwise secured together by mechanical 25 fastenings, or they may be spot welded or otherwise secured together by processes of a similar character.

The matter of prime importance in connection with the production of a device of 30 this character is that the anchorage of the arms shall be such that they cannot be dis-

engaged from their fastenings by a direct outward pull, and that the said carrier may not have such movement with relation to the running board as to permit the escape 35 of packages by reason of such movement.

I claim:

1. In a luggage carrier for automobiles, arms adapted to extend outwardly beyond the edge of a running board, means for 40 anchoring the inner ends of the arms to the running board, the said arms resting on the running board at its outer edge, and a member forming a part of an extension of the frame of a resilient construction projecting under the edge of the running board 45 and shaped to bear against the under surface of the said running board and applicable thereto and removable therefrom by the tortion of the carrier structure. 50

2. In a luggage carrier for automobiles, arms having substantially angularly disposed inner ends adapted to be applied to anchors on the running board, a frame structure constituting a guard carried by the said 55 arms, and an extension attached to the frame between its ends and adapted to project under the running board into contact with its under surface and adapted to be removed therefrom by the springing of the 60 said guard.

JOHN W. GORRELL.
